J. ALLINGHAM.
WASTE AND SUPPLY VALVE.
APPLICATION FILED AUG. 27, 1910.

1,233,634.

Patented July 17, 1917.

UNITED STATES PATENT OFFICE.

JAMES ALLINGHAM, OF CHICAGO, ILLINOIS.

WASTE AND SUPPLY VALVE.

1,233,634.

Specification of Letters Patent. Patented July 17, 1917.

Application filed August 27, 1910. Serial No. 579,217.

To all whom it may concern:

Be it known that I, JAMES ALLINGHAM, a citizen of the United States, residing at Chicago, in the county of Cook and State 5 of Illinois, have invented certain new and useful Improvements in Waste and Supply Valves for Bath-Tubs, Washbowls, and the like, of which the following is a specification.

10 This invention relates to improvements in valve mechanism, for supplying and discharging water to and from bath-tubs, washbowls, sinks, and the like.

The principal object of the invention is 15 to provide means whereby water from supply pipes may be conducted through the waste tube and waste opening, into a vessel without producing noise or splashing, and thereby mixing the same; and whereby 20 the water in a vessel may be discharged to the sewer, through the same passage; and the walls of the vessel may be free of perforation and obstructions for convenience in cleaning the same. Another object of the 25 invention is to provide automatic means for preventing water from overflowing the vessel and automatic means for cleaning the waste passages, leading from the vessel. Another object of the invention is to provide 30 means whereby the water from the supply may be conducted into a vessel, through the waste tube and waste opening thereof, and forced into a stand pipe within the vessel, which may be used for spraying or for filling 35 portable vessels and means for checking the flow and forcing it through the waste passages for cleansing the same.

These and other objects and advantages 40 of the invention will be fully explained in the following specification; and its novel features and arrangement of the different parts will be fully pointed out in the claims.

Referring to the accompanying drawings,—

45 Figure 1, is a central sectional view partly in elevation showing the invention attached to a vessel;

Fig. 2, is a transverse sectional view of the invention taken on line 2—2 of Fig. 1, 50 looking in the direction indicated by the arrows, showing the supply valves and the waste valve connected together and the stems thereof secured in a fixed position relative to each other, also showing one form of

an automatic and manually operated waste 55 valve arrangement;

Fig. 3, is a top plan view of the base plate, for supporting a stand pipe shown in Fig. 1, of the drawings:

Fig. 4, is a top plan view of a strainer 60 plate showing perforations;

Fig. 5, is a view in side elevation of the waste valve, as shown in Figs. 1, and 2, of the drawings;

Fig. 6, is a top plan view of the same; 65

And Fig. 7, is a central sectional view of a modification of the invention showing the automatic waste valve seated in the lower wall of the inner chamber, and arranged for automatic and manual actuations. 70

In the drawings, like numerals indicate like parts, in all the figures.

The reference numeral 2, is a waste valve casing, (see Figs. 1, 2, and 7,) which may be constructed in any desired form, preferably as shown in the drawings, and having oppositely disposed openings 3, connecting with the water supply tubes 4, secured to the walls of said openings by means of screw-threads, or in any other desired manner. 80

The outer ends of said tubes are connected with the supply valve casing 6, by means of lip unions 7, or in any desired manner. Suitable supply pipes 8, are provided and 85 connected with the supply valve casing 6, and secured thereto by means of lip unions 9, or in any desired manner, (see Fig. 2,) said supply pipes communicate with the interior of the supply valve casing 6, and with the hot and cold water supply. Suitable supply valves 10, are seated within the casing 6, (see Fig. 2,) and suitable stems 11, secured to said valves and extended through stuffing-boxes 12, to any desired distance, 90 above the same, said stems being provided with knobs 13, for operating the same in opening and closing the valves.

In this construction I have shown an ordinary compress valve, but any form of supply valve may be used, without departing from the principles of the invention, said construction showing means for connecting with both the hot and cold water supply. 100

In the lower wall of the waste valve casing 2, (see Figs. 1, 2, and 7,) is provided an opening 14, having a drain pipe 15, communicating therewith and secured to the 105

walls thereof in any desired manner, preferably by means of a slip joint connection 16. The said drain pipe is arranged to connect with the sewer, into which the waste water is conducted. Between the openings 3, in the walls of the casing 2, (see Figs. 1 and 7,) is provided an opening 17, having a horizontally disposed tube 18, communicating therewith and secured to the 10 wall of said opening, by means of a slip joint connection 19, or in any other desired manner, the said tube is provided with an inclosed end 20, and an opening in its upper wall 21, and a vertical extension 22, extended above the opening, said extension having a peripheral flange 23, thereon for registering with an opening 24, in the bottom of a vessel 25. A peripheral flanged nipple 26, is extended through the opening 24, in the vessel and is screw-threaded to the 20 vertical extension 22. Thus supporting the tube 18, in position and affording communication between the vessel 25, the supply valve casings 3, and the drain pipe 15, whereby the water from the supply may be 25 conducted into the vessel and drain pipe without noise or splashing. In its passage through the tube 18, the hot and cold water will be thoroughly mixed before entering 30 the vessel and the hot water being conducted through the bottom of the vessel, lessens the danger of scalding.

A suitable strainer 27, (see Figs. 1, and 4,) is provided, having a screw-threaded opening 28, in its center, said strainer may 35 be cast integral with the flange nipple 26, or otherwise joined to the nipple in any desired manner. Said strainer is for the purpose of preventing articles of value from 40 entering the tube 18, and also for the purpose of registering with and supporting a detachable stand pipe 29, the said stand pipe is formed of a tube having a valve 30, arranged therein for regulating the flow of 45 water, and having a nozzle 31, secured above the valve for discharging the same. The tube is secured to a base plate 32, and registers with an opening 33, in said plate (see Fig. 1,) which plate is provided with 50 a transverse bar 34, extended across said opening, and a screw-threaded stud 35, rigidly secured to and extended below said bar. The said stand pipe is held in position by screwing the stud 35, into the opening 28, in the strainer 27, and the outer 55 margins of the base plate and strainer is provided with a ground or gasket joint for preventing the water from entering the vessel and for directing it into the stand pipe 60 for the purpose of spraying or filling portable vessels.

In the opening 17, of the casing 2, is provided a lateral extension 38, projecting into the casing. The said extension is formed 65 integral with the side walls of said casing,

and otherwise spaced apart therefrom, forming chambers 39, and 40, and the supply openings 3, communicate with said chamber 40. The water introduced through openings 3, will enter chamber 40, and pass 70 through the tube 18, into the vessel 25. In the upper wall of the waste valve casing 2, is provided an opening 43, (see Figs. 1, 2, and 7,) a tube 44, is secured to and extended any desired distance above said casing. A stem 45, provided with a knob 46, is extended through the tube 44, and opening 43, and secured to a waste valve 41, (see Figs. 1, and 2,) which is seated in the upper wall 42, of the extension 38. In these 75 views I have shown the valve arranged for vertical automatic movement on the stem by means of a vertical extension 47, on the valve 41, having an elongated slot 48, therein to receive a pin 49, which is secured to the stem 45, and extended through the slot 48, of the extension 47. The above construction is for preventing the overflowing of the vessel.

From the foregoing description it may be 90 seen that the valve will actuate independent of the movements of the stem, but I do not want to confine myself to the specific construction for it is obvious that the stem 45, may be rigidly secured to the valve 41, and 95 be subject to automatic movement with the valve and by reason of a fluctuating pressure of water in a vessel; and the relative pressure actuation may be predetermined by means of a fixed weight of the valve or of 10 the valve and stem combined, or it may be predetermined by means shown in the modification, (see Fig. 7,) in which the valve 41, is seated for downward movement, in the lower wall of the extension 38, in the 11 valve casing 2, and having a compress spring 54, supported in the opening 43, of said casing and vertically extended into the tube 44, and encircling the stem 45. Said stem is provided with a pin which rests on the 11 spring 54, the tension of said spring may be arranged to actuate at a predetermined pressure on the valve. For securing the upper portions of stems 11, in a fixed position relative to the tube 44, (see Fig. 2.) 1 A tie brace 50, is provided which may be horizontally adjustable and having at its outer ends a loose connection 51, with the stems 11, and a rigid connection 52, with the tube 44, which connection is formed of 1 a circular band having a set screw 53, securing said band to the tube.

From the drawings and foregoing description the construction and functions of the device is apparent. It is also apparent that 1 this invention is susceptible of other modifications and variations in its construction not shown or described, without material departure from the spirit and principles of the invention, and for this reason I do not

wish to confine myself to the exact construction shown and described in practically carrying out the novel features of the invention.

5. Its operation is as follows, to supply the vessel 25 with water open supply valves 10 when a predetermined quantity of water is secured in the vessel, the valve 41 in the waste valve casing 2 will automatically move 10 by means of abnormal pressure of water and thereby the flow from the supplies will be turned directly through the discharge aperture 14 into the drain 15 and thereby preventing the water from overflowing the 15 vessel. To discharge all the water from the vessel 25, open the valve 41 in the waste valve casing 2 by means of the manual operating knob 46 and stem 45 and all the water in the vessel will return to the waste valve 20 casing and pass through the discharge aperture 14 into the drain.

For the purpose of spray and for filling portable vessels such as pails, slop jars, water pitchers and the like, secure the stand 25 pipe 29 in position over the waste aperture 24 in the vessel 25. In this position the water from the supplies will be directed into said stand pipe and by opening the valve 30 water may be drawn from the nozzle 31 for the purposes above mentioned.

Having thus fully described my invention what I claim as new and desire to secure by Letters-Patent is—

1. A valve of the character described, consisting of a vertically disposed oblong integral casing having means in its side wall about midway between its ends, communicating with a horizontally disposed conduit, said conduit communicating with the interior of a vessel, means in the side wall of said casing about midway between its ends communicating with water supply, and means in its bottom wall, communicating with a drain pipe, a valve seated within and 45 near the center of said casing, and having one of its sides for contact with water pressure for automatic reciprocating movement thereby, a vertically disposed stem, having manually operative means thereon and extended through the top wall of said casing for 50 slidable movement therein and connected with said valve and mounted for automatic vertical movement of said stem and valve.

2. A mechanism of the character described, 55 consisting of a casing communicating with water supply for induction and communicating with a drain pipe for eduction, a vessel having a waste aperture therein communicating with said casing, a stand pipe within 60 said vessel communicating with said aperture, automatic and manual operative means in said casing for preventing abnormal pressure of water in said stand pipe and for positively discharging water therefrom.

65. 3. A mechanism of the character described,

consisting of a casing communicating with water supply for induction and communicating with a drain pipe for eduction, a vessel having an aperture therein, a conduit communicating with said aperture in said vessel, and 70 communicating with said casing, a stand pipe within said vessel having a valve and a nozzle thereon, and communicating with said waste aperture in said vessel, a valve seated in said casing for directing water, a 75 stem on said valve extended through said casing, and having manual means thereon for operating said valve.

4. A mechanism of the character described, 80 consisting of a casing communicating with water supply for induction and communicating with a drain pipe for eduction, a vessel having a waste aperture therein communicating with said casing, a stand pipe within said vessel having a nozzle thereon 85 and communicating with said aperture, means on said stand pipe for controlling the flow of water therein, automatic and manually operative means in said casing for preventing abnormal pressure of water in said 90 stand pipe and for positively discharging water therefrom.

5. A mechanism of the character described, 95 consisting of a casing communicating with water supply for induction and communicating with a drain pipe for discharging water, a vessel having an aperture therein, a stand pipe within said vessel, having a nozzle and a valve thereon, and communicating with said aperture within said vessel, a horizontally disposed conduit communicating with said casing, and in communication with said stand pipe for conducting water into and out of said stand pipe, a valve seated in said casing, having one side thereof for contact with water pressure for automatic reciprocal movement thereby for preventing abnormal pressure in said stand pipe, a stem having manually operative means thereon extended into said casing and connected 100 with said valve for positively actuating said valve.

6. A mechanism of the character described, 115 consisting of a casing communicating with water supply and with a drain pipe, a valve seated in the casing, a stem having manually operative means thereon extended into the casing and secured to said valve, a vessel having a waste opening in its bottom, a stand pipe within said vessel communicating 120 with said waste opening and extended above the same, a horizontally disposed conduit communicating with said casing and with said waste aperture and stand pipe.

7. A mechanism of the character described 125 consisting of a casing communicating with water supply and with a drain pipe, a vessel having an aperture in its lower portion, a conduit communicating at one of its ends with the vessel through said aperture and 130

at its other end with said casing, a stand pipe having an apertured base plate on its lower part detachably secured to the vessel around and over the aperture therein, a 5 valve seated in the casing, a stem having manually operated means thereon and extended in the said casing and connected to

said valve for the purpose of actuating the same.
